UNITED STATES PATENT OFFICE.

WILLIAM MANUEL NICOL, OF HILDEBRAND, SASKATCHEWAN, CANADA.

ATTACHMENT TO BINDERS.

1,130,757.

Specification of Letters Patent. Patented Mar. 9, 1915.

Application filed November 28, 1913. Serial No. 803,554.

To all whom it may concern:

Be it known that I, WILLIAM MANUEL NICOL, of the post-office of Hildebrand, in the Province of Saskatchewan, Canada, 5 have invented certain new and useful Improvements in Attachments to Binders, of which the following is the specification.

The invention relates to improvements in attachments to binders especially to the breastplate of a binder and the object of the invention is to provide an attachment to the breastplate which will prevent the straw passed over the deck and tied by the needle from becoming stuck or jammed in the 15 breastplate as very often occurs.

With the above object in view the invention consists essentially in a spring actuated guard plate associated with the breastplate and operating over the slot in the breast- 20 plate, the parts being arranged and constructed as hereinafter more particularly described and later pointed out in the appended claims.

Figure 1 represents a side view of a portion of the deck, the breastplate and other associated parts of a binder with my invention applied. Fig. 2 represents a plan view of the latter parts. Fig. 3 represents an enlarged detailed perspective view of the 25 guard plate. Fig. 4 represents a vertical sectional view through the breastplate, the section being taken in the plane denoted by the line X—X' Fig. 2. Fig. 5 represents an enlarged detailed face view of the eye and adjoining parts. Fig. 6 is a section taken on line y'—y' of Fig. 2.

In the drawings like characters of reference indicate corresponding parts in each figure.

40 1 represents the deck of a binder, 2 the apron, 3 the needle carried by the needle shaft 4, 5 the packers carried by the packer crank shaft 6, 7 the deflector, 8 the breastplate and 9 a suitable brace bar supporting the breastplate and deflector.

45 10 represents the binder attachment of which 11 is the post or standard, 12 the discharge arm shaft and 13 the discharge arms.

14 represents a grain guide extending 50 from the breastplate and located more or less directly above the apron.

The breastplate is constructed as is customary with two flaring side walls 8' and 8" and is provided with a slot 8³ to receive the 55 needle when the same is swung upwardly.

The above parts are all of ordinary con-

struction and are herein described in order that one may have a better idea of the application and operation of my device.

It is explained that the needle shaft is rotated to swing the needle upwardly toward the breastplate, the advancing end of the needle passing into the slot and advancing in the continued rotation of the needle shaft toward the outer end of the breastplate.

In actual practice the straw or grain passed over the deck is very often jammed into the slot in the breast plate by the needle when it is swung up, with the result that one has to stop the binder and clean out 70 the straw before further work can be proceeded with. My invention which is designed to overcome this difficulty is now explained in detail.

15 is a grain shield permanently secured 75 by bolts or rivets 16 to the breastplate, the shield having the body portion thereof located directly beneath the under side of the breastplate and provided with a slot 15' registering with that 8³ in the breastplate. 80 Brackets 17, 18 and 19 are also supplied to support the shield from the breastplate.

20 is a guard plate of the form best shown in Fig. 3 of the drawing which guard plate is pivotally secured to the breastplate and 85 the shield by a pivot bolt 21, the guard being located between the shield and breastplate, there being sufficient space reserved between these parts to form a guide way for the guard. The free or extending end of 90 the guard is designed to swing across the slots 8³ and 15'.

It is here to be noticed that the bracket 18 is connected to the shield by an eye bolt 18', the eye 18² of which receives slidably 95 one end of an actuating rod 22, the other end of which is turned or bent downwardly and pivotally connected to the guard plate by flaring the head and countersinking it in the under face of the guardplate, (see 100 Fig. 6.)

22' is an adjusting nut on the rod and 23 and 24 are washers placed on the rod which washers receive between them a spiral spring 24'. This spring is arranged to hold 105 the guard plate normally in the position shown in Fig. 2 of the drawing.

In the actual operation of the binder the needle primarily engages with the guard plate when swinging upwardly and as it 110 continues to advance it carries the guard plate ahead of it for the remainder of the

stroke. The guard plate entirely prevents straw from being passed into the slots by the needle.

I have shown in dotted outline in Fig. 1 the position which the plate has in respect to the needle when the needle initially engages with the guard plate.

It will be seen that if any straw is gathered on the needle it will be swept off by the guard plate and not allowed to enter the slots. As the needle swings over, the guard plate rides continuously on the adjoining face thereof and sweeps down any straw it might otherwise have a tendency to pass up.

In order to limit the back position of the guard plate I have provided a stop secured to the breastplate. This is shown in the form of a bolt simply passed through the breastplate and provided with a nut acting as a stop.

What I claim as my invention is:

1. The combination with the breastplate of a binder, said breastplate having the usual needle slot therein, of a shield carried by the breastplate and provided with a slot registering with the slot in the breastplate, a guard pivotally secured to the shield at

one side of its longitudinal center and located between the shield and the breast- 30 plate, said guard being adapted to pass across the slots and a spring connected with the guard, as and for the purpose specified.

2. The combination with the breastplate of a binder, said breastplate having the usual needle slot therein, of a shield carried by the breastplate and provided with a slot registering with the slot in the breastplate, an eye carried by said shield, a guard pivotally secured to the shield at one side of its 40 center and located between the breastplate and shield, said guard being adapted to pass across said slots, an actuating rod having one end pivotally secured to the guard and the opposite end slidably mounted in said 45 eye, an adjusting nut on the rod on the end remote from the eye and a spring inserted on the rod between the eye and the nut, as and for the purpose specified.

Signed at Arcola this 17th day of November, 1913.

WILLIAM MANUEL NICOL.

In the presence of—

A. E. VROOMAN,
NELLIE HOEY.
